UNITED STATES PATENT OFFICE.

ARCHER H. BURR, OF OMAHA, NEBRASKA.

RADIATOR ATTACHMENT.

Application filed October 14, 1921. Serial No. 507,781.

To all whom it may concern:

Be it known that I, ARCHER H. BURR, a citizen of the United States, residing at Omaha, in the county of Douglas and State of Nebraska, have invented certain new and useful Improvements in a Radiator Attachment, of which the following is a specification.

This invention relates to an attachment for radiators of internal combustion engines, and has for its object to provide means automatically operative by the forward movement of the vehicle, tending to prevent undue heating of the water in the radiator and water jacket.

The invention consists of the novel construction, combination and arrangement of parts as described herein and claimed, and as illustrated in the accompanying drawing, 20 wherein,

Fig. 1 is a view in side elevation showing a part of a radiator with the device mounted thereon. Fig. 2 is a view of the attachment in longitudinal section, also 25 showing the upper part of a radiator in transverse section.

Referring now to the drawing for a more particular description, the device is shown and described in connection with the top 30 portion of a radiator 3 of an internal combustion engine, the usual collar for the radiator being indicated at 4.

It is well known that the water in the radiator often becomes unduly heated, especially when an automobile is driven for a considerable time at a high rate of speed, the excessive heat causing too rapid evaporation of water and often resulting in injury to the engine. In order that the degree of heat may be reduced and that, approximately, a uniform degree of temperature of water may be maintained, I provide means for that purpose which operates automatically by the forward movement of the vehicle, said means consisting, broadly, in a draft-pipe 5 disposed above and communicating with the radiator, which permits escape of heated air, and a funnel 6 having a pipe 7 traversing the draft-pipe and extending within the radiator, for conducting thereto air from the atmosphere, the result being that the heated air will be moved outwardly through the pipe 5 by force of the cool air which enters the radiator through 55 the conducting-pipe 7 and funnel.

In order that dust or other foreign substances will be excluded from the funnel a foraminous web 8 is provided therefor, and at α is indicated a similar web for the top of the pipe or sleeve 5.

In order that the parts may be conveniently assembled, the convergent part or sleeve a of the funnel is threaded upon the horizontal end-portion of the conducting-pipe 7, and it will be understood that, by 65 rotating the funnel in one direction, the flange c of said conducting-pipe will be pressed firmly against the inner side of the draft-pipe 5, which operates to dispose and maintain the axis of the funnel approximately at right-angles to the axis of said draft-pipe.

Numeral 9 indicates a sleeve operating as a coupling, said sleeve having a threaded connection with the collar 4 of the radiator, and having a flange d ; and at 10 is indicated a locking-ring having a threaded connection with the draft-pipe 5, and having a flange e adapted, when rotated, to engage the flange d for removably securing the pipe 5 to the 80 sleeve 9, in a vertical position.

When it is desired to supply the radiator with water, the foraminous cap 11 may be removed, or the pipe 5 may be rotated in one direction for disconnecting it from the 85 locking-ring 10, which permits its removal, together with the funnel and conducting-pipe.

While I have described details of construction, I do not wish to be understood as 90 limiting myself in this respect, and changes in minor details, as well as the form, size, and proportion of parts may be changed, as found to be of advantage, said changes to be determined by the scope of the invention as claimed.

It will be appreciated that, since the pipe 5 projects considerably above the top of the radiator, it will discharge heated air to advantage. Also, since the discharge port of 100 the pipe 7 is disposed interiorly of the radiator, the cool air conducted thereby will operate to advantage in condensing and forcing the heated air outwardly of the draft-pipe.

I claim as my invention:

In a radiator attachment, an upright air draft pipe in communication with and extending above the top of the radiator, a conducting pipe for cool air having a horizontal, 110

2
threaded part provided with a flange and traversing the side of the air draft pipe and having a vertical part within said air draft pipe extending within the radiator, a 5 funnel provided with an interiorly threaded sleeve at its convergent end, said funnel being adapted to be disposed at the side of the air draft pipe with its sleeve engaging the threaded part of the conducting pipe, and

being revoluble for moving the flange of 10 the conducting pipe and said sleeve into engagement with the wall of the air draft pipe.

In testimony whereof, I have affixed my signature in presence of two witnesses.

ARCHER H. BURR.
